Serial No. 251,634

8 Claims. (Cl. 260—570.5)

1

This invention relates to new derivatives of ethylenediamine and particularly relates to such derivatives of ethylenediamine, where three of the hydrogens of the amino groups are replaced by alkyl radicals and the fourth one by an alpha-naphthyl radical.

These new compounds are represented by the following general formula:

in which R is a long chain alkyl radical containing 6 to 14 carbon atoms, R¹ and R² are short chain alkyl radicals containing 1 to 3 carbon atoms. R¹ and R² may be, but are not necessarily alike.

The compounds of our invention have a very remarkable antifungal activity. In vitro, they show fungistatic activity against many fungi even in a dilution of 1:400,000. This activity is apparently a function of the alkyl substituents in R. In compounds where R is a short chain alkyl radical like methyl, ethyl even butyl, the antifungal activity is only slight. Where this radical is hexyl or a higher alkyl group, the activity surprisingly increases, as can be seen from the following table:

Minimal fungistatic concentrations (mg./%)

Fungus Tested	In the compounds of this table R ¹ and R ² are both methyl and R is—						
	methyl	ethyl	butyl	hexyl	octyl	nonyl	deeyl
<i>Trichophyton mentagrophytes</i>	4	4	64	<0.25	<0.25	<0.25	<0.25
<i>Trichophyton rubrum</i>	4	8	4	<0.25	<0.25	<0.25	0.5
<i>Sporotrichum Schenckii</i>	2	8	16	<0.25	<0.25	<0.25	2
<i>Epidermaphyton floccosum</i>	2	4	0.5	<0.25	<0.25	<0.25	1
<i>Microsporum canis</i>	8	8	8	0.5	1.0	0.5	4
<i>Microsporum adovini</i>	4	8	4	<0.25	0.5	<0.25	2
<i>Candida albicans</i>	>64	32	>64	2.0	2.0	1.0	>8

These in vitro tests against pathogenic fungi indicate the utility of our compounds against fungus infections of the skin. Such infections are ringworm of the scalp, barber's itch, athlete's foot and others. We have employed the hydrochlorides of our compounds in hydrophilic ointment with gratifying results. The ointment was made up from 0.5 to 2% in strength. Lotions may be prepared by dissolving our compounds in suitable vehicles.

To prepare the compounds of our invention we prepare first the alkynaphthylamines, by react-

ing α -naphthylamine with a long chain alkylbromide in which the alkyl radical contains 6 to 14 carbon atoms and purify the product by distillation. Then we prepare the sodium salt of the intermediate alkynaphthylamine by reacting it with sodiumamide. The sodium salt is then reacted with β -dialkylaminoethyl chloride in which the alkyl radical contains 1 to 3 carbon atoms in a nonpolar solvent, after which the desired new compound is separated and purified, as described in the specific example below.

The products so obtained are high-boiling, viscous, oily liquids, soluble in the usual organic solvents. They are insoluble in water, but form a water soluble addition salt with hydrochloric and other acids.

The following is an illustrative example of our preferred procedure of carrying out our invention, which is given for illustration and not for limitation.

20 Preparation of one of the intermediates:

300 grams (2.11 moles) of α -naphthylamine were dissolved in 500 mls. of ethanol and to this 340 grams (1.76 moles) of octyl bromide were added. The solution was refluxed for 48 hours after which the ethanol was removed by distillation. The semisolid residue was placed in 100 mls. of water which was made alkaline with sodium hydroxide solution (40%) to pH 10.0 and

Preparation of one of the products:

amine, the above prepared intermediate, was dissolved in 250 mls. of xylene and 23.5 grams (0.6 mole) of sodium amide was added. It was slowly heated up to 90° C. and was kept at that temperature for thirty-six hours. The mixture was allowed to cool to room temperature and 53.75 grams (0.5 mole) of β -dimethylaminoethyl chloride was added. The reaction mixture was then heated to 105–110° C. and kept at that temperature for forty-eight hours under continuous stirring. The reaction mixture was then allowed to cool to room temperature and acidified to a pH of 1.0 with a 1:1 HCl solution. The aqueous layer was separated from the xylene layer, cooled and the pH adjusted to 10.6 with sodium hydroxide solution (40%). The aqueous alkaline mixture was extracted three times with ether. The combined ether extractions were dried with KOH pellets. After separating from the KOH pellets, the ether was distilled off on the steam bath. The residue was fractionated in vacuum and the fraction between 102–109° C. at 3 mm. was collected. The product, N- α -naphthyl,N-octyl,N',N'-dimethylethylenediamine forms a viscous, oily liquid. It was obtained in about 52.3% yield. In a nitrogen determination (Micro-Dumas) there was found: N=8.39% (theory=8.60%).

Preparation of the water soluble hydrochloride of above compound:

3.26 grams (0.01 mole) of N- α -naphthyl,N-n-octyl,N',N'-dimethylethylenediamine was dissolved in 50 mls. of dry ether. To this solution was added 0.36 grams (0.01 mole) of HCl dissolved in ether. The solutions were intimately mixed and cooled over night. The precipitate was then collected, washed with dry ether and recrystallized from a mixture of isopropanol and ether. The melting point of the hydrochloride is 102–104° C. In a nitrogen determination (Micro-Dumas) there was found N=7.60% (theory=7.55%).

Following the above procedure, a number of our compounds were prepared, differing in the length of the alkyl radical in the R substitution. They have the following characteristics:

R	Boiling Point	Nitrogen Determination	
		Found, Percent	Theory, Percent
H.....	166–8° at 1 mm.....	13.20	13.10
CH ₃	156–9° at 3 mm.....	12.39	12.40
CH ₂	177–8° at 3 mm.....	10.38	10.20
CH ₃	166–8° at 1 mm.....	9.15	9.40
CH ₂	179–81° at 1 mm.....	8.73	8.98
CH ₃	185–7° at 1 mm.....	8.65	8.60
CH ₂	186–8° at 1.5 mm.....	8.11	8.20
CH ₃	199–202° at 1.5 mm.....	8.07	7.92

The hydrochloride of the last compound (R=C₁₀H₂₁) melts at 93–4° C. In the nitrogen determination was found N=7.39% (theory=7.37%).

As can be seen from our specifications the compounds of our invention present highly valuable and unexpected fungistatic properties especially

against pathogenic fungi, although their usefulness is not limited to that particular group.

We do not limit ourselves to the specific limitations mentioned, as these are given solely for the purpose of clearly describing our invention as set forth herein.

What we claim is:

1. Compounds of the group consisting of alpha-naphthyl, tri-alkylethylenediamines of the general formula:

where R is an alkyl radical containing 6 to 14 carbon atoms, R¹ and R² are alkyl radicals containing one to three carbon atoms, and their water soluble hydrochlorides.

2. N - alpha - naphthyl -, N - hexyl -, N',N'-dimethyl-ethylenediamine.

3. N - alpha - naphthyl -, N - heptyl -, N',N'-dimethyl-ethylenediamine.

4. N - alpha - naphthyl -, N - octyl -, N',N'-dimethyl-ethylenediamine.

5. N - alpha - naphthyl -, N - nonyl -, N',N'-dimethyl-ethylenediamine.

6. N - alpha - naphthyl -, N - decyl -, N',N'-dimethyl-ethylenediamine.

7. The method which comprises reacting α -naphthylamine with a long chain alkylbromide to produce an alkylnaphthylamine containing a long chain alkyl radical, preparing the sodium salt of the last named compound, and reacting the said sodium salt with β dialkylaminoethylene chloride.

8. The method which comprises reacting α -naphthylamine with a long chain alkylbromide having 6 to 14 carbon atoms to produce an alkyl-naphthylamine containing a long chain alkyl radical, preparing the sodium salt of the last named compound, and reacting the said sodium salt with β dialkylaminoethylene chloride in which the alkyl radical contains 1 to 3 carbon atoms.
